UNITED STATES PATENT OFFICE

above the bottom of the cylinder. Into this tube there extends a pipe 66 which is taken through the bottom of the cylinder, and which terminates short of the level of the end of the pipe 6. In the 5 extreme upper portion of the cylinder there are provided holes 67. The pipe 66 leads from the evaporator to the suction side of the compressor and issues at 68.

In the form of construction shown in Fig. 2 10 the evaporator consists of a casing 69 in which there is disposed a container 70 which is made into communicating compartments A and B by the provision of a partition wall 71. The compartment A of the container is provided with a 15 cover 72 through which the pipe 6' coming from the reduction valve debouches. Into the compartment B, which is open at the top, there extends a tube 66' which is connected to the suction side of the compressor. In the outside wall 20 of the compartment A there is provided an overflow 73. The lower end of the tube 66' is at a lower level than this overflow.

The cooling medium vapor passing during the 25 operation of the machine through the non-return valve 2 and pipe line 3 into the condenser 4 is cooled in a known manner, and consequently condensed. The condensate then passes through the pipe 3' into the regulating valve 5. On the attainment of a certain level in the casing of the 30 valve 5, the float member 56 is lifted and the cooling medium passes through the valve 61 and pipe 6 into the cylinder 64 of the evaporator 7. The lubricant carried along with the cooling medium falls to the bottom and rises in the tube 65 under 35 the weight of the cooling medium superposed thereon until it reaches the orifice of the tube 66 and can be drawn off by the compressor. In addition the cooling medium vapor is constantly sucked back into the compressor through the 40 tube 66.

In the form of construction shown in Fig. 2 the

liquefied cooling medium passes through the pipe 6' into the compartment A of the container 70 in which the lubricant descends, passes over into the compartment B, and there rises until it reaches the lower end of the pipe 66', so that the lubricant can be drawn off to the compressor through this pipe. 5

Both forms of construction provide perfect separation of the cooling liquid from the lubricant, and permit with certainty of returning the 10 lubricant to the compressor.

In consequence of the independence of the returning of the lubricant, irrespective of the level of the liquid in the evaporator, the degree of filling of the machine with cooling agent can vary with 15 in fairly wide limits. Losses through escaping of cooling agent likewise are of no consequence. The arrangement of the communicating vessel within the evaporator has the particular advantage that the cooling medium in the communicating vessel is protected against the intrusion of heat through the evaporator or through the cooling liquid contained therein, so that the separation of the two media can take place unimpeded. 20

I claim:

1. A lubricating separator for compression refrigerating machines comprising an evaporator and a communicating vessel, said communicating vessel having two hollow fluid receiving legs, one of said legs being adapted to receive a column of 25 lubricant and a superimposed column of cooling fluid, the other of said legs being adapted to receive a column of lubricant alone, a suction pipe 30 connected to said second named leg, and said first named leg being provided with an overflow for 35 feeding the surplus cooling fluid to the evaporator.

2. A lubricant separator according to claim 1, characterized by the fact that the communicating vessel is disposed within the evaporator. 40
